JAMES R. BALSLEY, OF BEVERLY HILLS, CALIFORNIA, ASSIGNOR TO FOX FILM CORPORATION, OF HOLLYWOOD, CALIFORNIA, A CORPORATION OF NEW YORK

METHOD OF AND SYSTEM FOR RECORDING AND REPRODUCING SOUND

Application filed November 18, 1929. Serial No. 407,925.

This invention relates to the photographic recording and reproducing of sound; and has for its primary object improvement in the quality and perfection of sound reproduction.

Photographic sound records now used in the art are of two well known types, the sound waves being represented in the first type by a varying density band of constant width, and in the second type by a varying width band of constant density, both types of records being characterized, however, by varying opacity, and both types of records being applicable to the present invention. Sound is reproduced from such records by illuminating the sound record on the moving film through a narrow slit by means of a beam of light of constant intensity, the portion of the light beam transmitted through the film being modulated by the sound record thereon, and then striking a photo-electric cell to generate a modulated electrical current therein, which is finally reproduced as sound waves by means of a speaker unit.

The width of the light-slit is determined as a compromise between two opposing requirements. The narrower the slit is made relative to the physical lengths of the opacity variations of the sound record, the more accurate is reproduction; but the lower is the light intensity on the film, and consequently the lower is the level of reproduction. Thus an effort to increase accuracy of reproduction by narrowing the width of the slit is defeated beyond a certain point by an accompanying decrease in light intensity, which causes distortion by reason of causing operation on the non-linear portion of the film characteristic curve. A slit width of between .0008 and .001 of an inch is now accepted as the best compromise between these opposing factors in certain present systems; although a greater width would give better light intensity on the film, while a narrower width would give better accuracy of reproduction.

Stated in one aspect, is an object of my invention to provide a sound recording and reproducing system in which increased accuracy in reproduction is gained with the use of a light-slit of a given width.

This object is accomplished, briefly, by

stepping down or dividing by a given number the frequencies of the original sound-wave microphone current before recordation. There is thus produced a sound record in which the physical lengths of the individual opacity variations are increased relative to the light-slit by the number of times which the frequency of the original microphone current was stepped down, and in reproduction a corresponding increase in accuracy will be gained. In reproduction, the electrical current produced from the divided-frequency record is put through a frequency multiplier, properly tuned and balanced to match the frequency divider, which reproduces the original microphone current. The output of the frequency multiplier is then amplified and reproduced as sound waves in the usual manner.

The invention will best be understood from the following detailed description of systems for carrying the invention into effect, reference for this purpose being had to the accompanying drawings, in which:

Fig. 1 is a diagram showing a sound recording system including step-down frequency converter or "frequency divider";

Fig. 2 is a diagram showing a sound record reproducing system including a step-up frequency converter or "frequency multiplier"; and

Fig. 3 is a diagram showing a variational type of frequency multiplier.

The frequency divider utilized in the present invention may be of any type suited to the purpose. For instance, it may be the type of circuit included in the system illustrated in Fig. 1 of the drawings, which circuit is described in an article in the Proceedings of the Institute of Radio Engineers for February 1929, on pages 255-259.

As described in the article referred to, this circuit is similar to the Abraham-Bloch multivibrator circuit, modified in such a way that it becomes a step-down frequency converter. The multivibrator consists essentially of an aperiodic circuit in which oscillations are sustained by a triode excited by a second triode which provides the proper phase relation for maintenance. In its usual

form the multivibrator acts as source of high frequency oscillations controlled by a low frequency injected oscillation. In its usual form it therefore constitutes a frequency 5 multiplier or step-up frequency converter. The circuit in this usual form may be used in reproduction according to the present invention, as will hereinafter be explained.

As arranged in Fig. 1, however, the circuit 10 is controlled at a fundamental frequency which is an integral submultiple of the injected control frequency, thus making it a step-down frequency converter.

Referring now to Fig. 1, the letter M indicates a microphone which is connected to an 15 amplifier 10, conventionally illustrated as being of the vacuum tube type. The output leads 11 and 12 of amplifier 10 are connected into the plate circuit 13 of a frequency divider 14 through the medium of a vacuum tube 15, which tube acts as a one way relay to isolate amplifier 10 from reactions due to the 20 frequency divider. For certain separated ranges of values for condensers 16, the fundamental frequency of the frequency divider 25 assumes values which are submultiples of the frequencies injected through leads 11 and 12. The order of control of the frequency divider, or, in other words, the ratio of the injected 30 frequency to the oscillation frequency of the frequency divider circuit, is dependent upon the various constants of the frequency divider circuit; and a frequency division by a relatively small number or by a number as high as 35 100 or more is readily obtainable by varying these constants. The output leads 20 and 21 of the frequency divider, which carry an electrical current of stepped-down frequency, may be connected to a vacuum tube amplifier 40 24, and the output of amplifier 24 is conducted by means of leads 25 and 26 to a recording lamp 27. A light-slit 28 is positioned before lamp 27, and a lens 29 casts an image of the illuminated slit 28 upon a moving film 30 to 45 print a record 31 thereon of the divided-frequency current. It will be obvious that the individual opacity variations of record 31 will be increased in physical length over what they would be in usual recording, by a 50 factor equal to the step-down ratio of the frequency divider.

In reproduction, the film 30 within its divided-frequency record 31 is operated in the usual manner in conjunction with a light-slit 55 to produce an electrical current wave at the reduced frequency, and this electrical current wave is thereafter stepped-up or multiplied in frequency by the factor originally utilized in frequency division, thereby 60 producing the original sound wave current which may be reproduced as audible sound by means of a usual speaker unit.

For this purpose, the system of Fig. 2 may be utilized. The film 30 with the divided-frequency record 31 is moved before a light-slit

32, which slit is illuminated by means of an illuminant 33 and lens 34. Light rays transmitted through slit 32 are modulated in passing through the film by the opacity variations of the record 31, and these modulated light rays impinge on a photo-electric cell 35. The photo-electric cell 35 generates an electrical current varying in accordance with the record 31, and this current is conducted by means of leads 36 and 37 to the vacuum tube amplifier 38. The output leads 39 and 40 of amplifier 38 are connected to a frequency multiplier 41, which, in the system illustrated in Fig. 2, embodies an electrical circuit of the "multivibrator" type, similar 70 to that utilized in the frequency divider of the recording system. By properly balancing the constants of the frequency multiplier circuit 42, oscillations may be set up therein at a stepped-up frequency; and by carefully adjusting the frequency divider and frequency multiplier with reference to each other, the output frequency of the frequency multiplier may be perfectly matched with the frequency of the original input current 75 injected into the frequency divider.

The output leads 45 and 46 of the frequency multiplier may be connected to a vacuum tube amplifier 47, and the output leads 48 and 49 thereof are connected to a speaker unit 50.

The general operation of the system may briefly be summed up as follows: The sound wave current produced by the microphone is divided in frequency by a selected number, 100 and the divided-frequency electrical current thereby produced is recorded upon a photographic film. The physical lengths of the individual opacity variations of the photographic record are then obviously increased by the factor of frequency division over what they would have been had the original sound wave current been recorded directly, and they are also increased by this same factor relative to the light-slit used in reproduction. And since, as has previously been explained, the accuracy of reproduction of a photographic record depends upon the physical lengths of the individual opacity variation relative to the width of the light-slit, 105 the divided-frequency record will be reproduced with an accuracy increased by the same factor over the highest accuracy possible in reproduction of usual full-wave sound records. A divided-frequency electrical current is then produced from the record with the use of a light-slit in the manner explained, and this current is then multiplied in frequency to match the original sound wave current injected into the frequency divider, 110 the multiplied-frequency current being finally reproduced as audible sound in the 115 usual manner.

The frequency divider and frequency multiplier are not necessarily of the type herein 120

illustrated and described, these being set forth merely for the purpose of simplicity of explanation.

Another form of frequency multiplier which may be mentioned is illustrated in Fig. 3. The frequency multiplier of this illustration, which will be understood to be adapted to replace the frequency multiplier in the reproducing system of Fig. 2, is a well known arrangement for doubling frequency, and will therefore be herein but briefly described. The input circuit 60 leads to the series connected windings of a pair of transformers 61 and 62, each equipped with a tertiary circuit 63 applied with current from a common battery B. The steady current through these windings is adjusted to bring the transformer fluxes just to the point where saturation occurs. The two primary windings in series being connected to a pulsating current, during the positive half cycles the flux in transformer 61 (wherein the m. m. f. of the primary winding assists the direct current winding), will change very little, while the flux in winding 62 will decrease considerably, since in this case the primary m. m. f. opposes the m. m. f. of the direct current winding. On the negative half cycle, the reverse is true. The flux of one transformer thus has a large variation during one alteration while the flux of the other transformer changes only slightly; and on the next alteration these conditions are reversed. The electromotive forces induced in the respective windings then combine, when the secondary windings 64 and 65 are connected reversed with respect to each other, to produce a double frequency electromotive force in the output circuit 66. Any number of such units can be used in cascade to provide any frequency multiplication required.

In all cases, the function of the frequency divider is to simplify the sound wave form relative to the light slit before recordation; and the function of the frequency multiplier is to duplicate the original sound wave form before audible reproduction.

It will be recognized that the illustrative system specifically described herein is capable of considerable modification and rearrangement without departing from the spirit and scope of my invention; and it is therefore to be understood that the following claims embrace all such modifications and equivalent arrangements as may fairly be construed to fall within the scope of my invention.

I claim:

1. The method of recording and reproducing sound, that includes transforming sound waves into electrical current waves corresponding thereto, producing therefrom an electrical current wave of stepped down frequency, making a record of said current wave of stepped down frequency, reproducing from said record its recorded electrical cur-

rent wave, producing therefrom an electrical current wave stepped up in frequency to match the original sound wave frequency and reproducing said last mentioned current wave as an audible sound wave. 70

2. The method of recording and reproducing sound, that includes transforming sound waves into electrical current waves corresponding thereto, producing therefrom an electrical current wave of stepped down frequency, making a photographic record of said current wave of stepped down frequency, reproducing from said record its recorded electrical current wave, producing therefrom an electrical current wave stepped up in frequency to match the original sound wave frequency, and reproducing said last mentioned current wave as an audible sound wave. 75

3. The method of recording and reproducing sound, that includes transforming sound waves into electrical current waves corresponding thereto, dividing the frequency of said electrical current wave by a given number, making a record of the divided-frequency current wave, reproducing from said record its recorded divided-frequency electrical current wave, multiplying the frequency of said divided-frequency current wave by the number originally used in frequency division, and reproducing said multiplied-frequency current wave as audible sound. 80

4. The method of recording and reproducing sound, that includes transforming sound waves into electrical current waves corresponding thereto, dividing the frequency of said electrical current wave by a given number, making a photographic record of the divided-frequency current wave, reproducing from said record its recorded divided-frequency electrical current wave, multiplying the frequency of said divided-frequency current wave by the number originally used in frequency division, and reproducing said multiplied-frequency current wave as audible sound. 85

5. In a sound recording and reproducing system, the combination of means for transforming sound waves into electrical current waves, means for dividing the frequency of said current waves by a given number, recording means for making a record of the electrical current wave so produced, means for reproducing the current waves recorded on said record, means for multiplying the frequency of said current waves by the number used in original frequency division, and means for reproducing sound waves from the multiplied-frequency current wave so produced. 90

6. In a sound recording and reproducing system, the combination of means for transforming sound waves into electrical current waves, means for dividing the frequency of

said current waves by a given number, photographic recording means for making photographic record of the electrical current wave so produced, means for reproducing the current waves recorded on said photographic record, means for multiplying the frequency of said current waves by the number used in original frequency division, and means for reproducing sound waves from the multiplied-frequency current wave so produced.

In witness that I claim the foregoing I have hereunto subscribed my name this 17th day of September, 1929.

JAMES R. BALSLEY.
